(57)

CLAIM

The ornamental design for a protective sleeve, as shown and described.

DESCRIPTION

FIG. 1 shows a perspective view of a protective sleeve; FIG. 2 shows a front view of the protective sleeve; FIG. 3 shows a rear view of the protective sleeve; FIG. 4 shows a right side view of the protective sleeve; FIG. 5 shows a left side view of the protective sleeve; FIG. 6 shows a top plan view of the protective sleeve; and, FIG. 7 shows a bottom plan view of the protective sleeve. The shade lines in the Figures show contour and not surface ornamentation.
